UNITED STATES PATENT OFFICE

1,973,902

WINDOW SCREEN STRUCTURE

Joseph E. Johnson, West Roxbury, Mass.

Application March 3, 1932, Serial No. 596,537

10 Claims. (Cl. 156—14)

This invention relates to a window-screen structure of the class wherein the screen frame is movable along guides secured to the window casing. Sometimes screen guides are made of wood, and sometimes they are made of metal. When they are made of metal, they are usually narrower and thinner than wooden guides. Accordingly, it is customary to make the screen dimensions to suit the particular kind of guides with which the screen is to be used. For example, when wooden guides are to be used, the screen is made narrower and its grooves larger than when metallic guides are to be used, because the wooden guides customarily are wider and thicker than metallic guides.

Wooden guides are apt to become broken or worn, and are generally unsatisfactory because they are apt to swell and to cause the screen frame to stick; or they shrink and allow the screen to become displaced and to drop out. For this reason, sometimes it is considered desirable to change the old installation by substituting metallic guides for the wooden guides. The present invention makes it easily possible to substitute metallic guides of the standard narrower width for the relatively wider and thicker wooden guides. This is accomplished conveniently by the provision of runners attached to the screen within its grooves to compensate for the difference in width and thickness between the old wooden guides which are to be replaced and the relatively narrower and thinner metallic guides. The nature of these runners is such that they can be attached quickly and conveniently to the screen frame. To compensate for variations within reasonable limits of the space between the two guides, the runners on at least one side are adjustable toward and from the associated guide.

The invention will best be understood by reference to the following description, when taken in connection with the accompanying drawing of one specific embodiment thereof, while its scope will be pointed out more particularly in the appended claims.

45 In the drawing:

Fig. 1 is an elevation, partly in vertical section, of a window-screen structure embodying the invention;

Fig. 2 is a horizontal, sectional view, on an enlarged scale, on line 2—2 of Fig. 1;

Fig. 3 is a horizontal, sectional view, illustrating the operation of removing or replacing the screen;

Fig. 4 is a perspective view of one of the non-adjustable runners;

55 Fig. 5 is a vertical, sectional view on line 5—5

of Fig. 2, illustrating one of the adjustable runners; and

Fig. 6 is an elevation, viewed from the right-hand side of Fig. 5.

Referring to the drawing, and to the window-screen structure illustrated therein, there is shown a window-screen 7, whose vertical members or stiles 8 and 9 are provided with usual grooves 10 and 11, to receive guides 12 and 13. These guides, as herein shown, are of the common metallic type hereinbefore alluded to. Usual springs 14, received in the groove 10, press against the adjacent guide 12, and provide sufficient resistance to maintain the screen in the desired position vertically with respect to the guides.

Since the metallic guides 12 and 13 are narrower and thinner than wooden guides, and since the width and depth of the grooves 10 and 11 is such as to receive wooden guides, it is necessary that the runners now to be described should not only fit into the grooves, but that they should compensate for the difference between the thickness of the wooden guides and metallic guides, as well as for their difference in width. In the case of the groove 10, which is customarily deeper than the groove 11, because of the use of the springs 14, I provide a plurality of runners 15, one of which is shown in perspective in Fig. 4. This runner has a head 16, to be received in the groove 10, and a shank 17, to be received in the screen frame. As herein shown, this shank is tapered, and pointed to enable it to be driven into place as by a hammer, and to retain the same securely in place, the shank is provided with means such as spurs 18. The head 16 is provided with a groove 19 to receive a guide 12. The width of the entrance of this groove is such (see Fig. 2) as to receive the guide with only sufficient clearance to enable the runner to travel easily along the guide. However, to facilitate removal and replacement of the screen by a horizontal swinging motion in the customary manner (see Fig. 3), but without danger of bending the guide, the sides of the groove 19 diverge inwardly. This enables the screen to be rocked relatively to the guide, without damage to the latter. In the present example, the horizontal dimensions of the head 16 are such that it fills the groove 10 in both directions.

At the other side of the screen, there are runners 20, each of which has a head 21 and a shank 22, the latter being tapered and pointed as in the case of the runner 15, and being also provided with lateral projections 23 to retain the same in place in the frame. But in this case, the lat-

eral projections are presented by a screw-thread, which has the advantage of easy application by means of a screw driver, and provides a means of adjustment to compensate for variations within reasonable limits of the space between two guides 12 and 13. This can be accomplished by simply screwing the shank of the runner into the screen frame to the desired depth. In this case, the head 21 as herein shown is tapered, and squeezes the wood of the frame sufficiently to produce considerable friction, tending to keep the runner from turning about its axis after it has been inserted to the required depth into the wood.

15 This runner is provided with a comparatively shallow groove 24, to receive the guide 13, and as the groove is shallow, there is no necessity for diverging sides, as in the case of the groove 19 of the runner 16. To reduce friction, the bottom 20 of the groove 24, instead of being straight or flat, is crowned (see Fig. 5), as by being formed of two surfaces which intersect each other in a point 25 contacting with the edge of the runner 13. This enables the runner to slide on the guide with minimum friction. Moreover, all four of the runners, even without the special provision just described, have so small an area in contact with the guides as to reduce friction very greatly, as compared with screen frames of the ordinary sort, 25 bearing throughout the length of their grooves on the guides. This in itself is an important and valuable feature.

Having thus described one embodiment of the invention, but without limiting myself thereto, 30 what I claim and desire by Letters Patent to secure is:

1. In a screen structure, the combination of a screen frame provided with two oppositely disposed grooves, two single guides centrally received in and separated from the bottoms and sides of said grooves, springs carried by said frame within said grooves, and resting against said guides, and two sets of runners carried by said screen frame within said grooves in spaces not occupied by said 40 springs and provided with central grooves receiving said guides, said runners being provided with integral shanks extending into said frame.

2. In a screen structure, the combination of a screen frame provided with two oppositely disposed grooves, two single guides centrally received in and separated from the bottoms and sides of said grooves, springs carried by said frame within said grooves, and resting against said guides, and two sets of runners carried by said screen frame within said grooves in spaces not occupied by said springs and running on said guides, said 50 runners being provided with central grooves receiving said guides having integral shanks extending into said frame, and said shanks being provided with lateral projections to retain said shanks in place.

3. In a screen structure, the combination of a screen frame provided with two oppositely disposed grooves, two guides received in and separated from the bottoms of said grooves, and two sets of runners carried by said screen frame within said grooves and running on said guides, one set of runners being provided with integral threaded shanks screwed into said frame, where- 60 by said runners may be adjusted toward and from the adjacent, associated guides by rotating said runners about the axes of said shanks.

4. In a screen structure, the combination of a screen frame provided with two oppositely disposed grooves, two guides received in and sepa-

rated from the bottoms of said grooves, and two sets of runners carried by said screen frame within said grooves and running on said guides, each runner having a head provided with a flat face which fills its groove from side to side, and a central groove receiving the associated guide, and a shank extending into said frame. 80

5. As a new article of manufacture, a unitary screen runner to be secured to a screen frame and to run on a guide, the same comprising a U-shaped head presenting a groove to receive the guide and an integral shank to be secured in the screen frame. 85

6. As a new article of manufacture, a screen runner to be secured to a screen frame and to run on a guide, the same being provided with a groove whose sides diverge inwardly from its entrance. 90

7. As a new article of manufacture, a screen runner to be secured to a screen frame and to run on a guide, the runner being provided with a groove whose bottom is longitudinally crowned. 95

8. In a screen structure, the combination of a screen frame provided with two oppositely disposed grooves, each having a bottom and two sides, two single guides centrally received between the sides of said grooves and separated from the bottoms and sides of said grooves, springs carried by one side of said frame within one of said grooves and resting against the guide in such groove, a set of runners carried by said screen within such groove, in spaces not occupied by said springs, and provided with grooves receiving such guide, and a second set of runners carried by said screen within the other groove and provided with grooves which receive the other guide. 100

9. In a screen structure, the combination of a screen frame provided with two oppositely disposed grooves, each having a bottom and two sides, two single guides centrally received be- 115

tween the sides of said grooves and separated from the bottoms and sides of said grooves, springs carried by one side of said frame within one of said grooves and resting against the guide in such groove, a set of runners carried by said screen 120 within such groove, in spaces not occupied by said springs, and provided with grooves receiving such guide, said runners being provided with shanks received in said frame, and the sides of said runners engaging the sides of such groove and preventing said runners from turning about said shanks as pivots, and a second set of runners carried by said screen within the other groove and provided with grooves which receive the other guide, said second set of runners being provided with shanks having screw-threaded engagement with said frame and being thereby axially adjustable. 125

10. In a screen structure, the combination of a screen frame provided with two oppositely disposed grooves, each having a bottom and two sides, two single guides centrally received between the sides of said grooves and separated from the bottoms and sides of said grooves, springs carried by one side of said frame within one of said grooves and resting against the guide in such groove, a set of runners carried by said screen within such groove, in spaces not occupied by said springs, and provided with grooves receiving such guide, a second set of runners carried by said screen within the other groove and provided with grooves which receive the other guide, and means for adjusting said second set of runners toward and from the first mentioned set of runners. 130
